UNITED STATES PATENT OFFICE.

ISAAC BROWN, OF NEW YORK, N. Y.

DENTAL ATTACHMENT.

1,315,085.

Specification of Letters Patent. Patented Sept. 2, 1919.

Application filed April 23, 1919. Serial No. 292,031.

To all whom it may concern:

Be it known that I, ISAAC BROWN, a citizen of the United States, and a resident of the city of New York, borough of Bronx, county of Bronx, and State of New York, have invented a new and Improved Dental Attachment, of which the following is a full, clear, and exact description.

This invention relates to dentistry. More particular it relates to removable bridge work employed in connection with the installation of artificial teeth in the patient's mouth.

An object of this invention is to provide certain removable bridge fixtures used for supporting artificial teeth. Another object of the invention is to provide a certain form of split pin dental fixtures to be used in connection with tubular supports such that the removable bridge work or artificial teeth can be periodically tightened to correct all looseness of the tooth, and to keep said tooth located in the patient's mouth in a positive and immovable relation.

Still another object of the invention is to disclose the various forms of split pin dental fixtures best adapted for the particular nature of work at hand. A broad feature of the invention resides in the use of flexible and springy expanding material for carrying out the above described purposes.

With the above principal objects in view the invention has relation to a certain arrangement and combination of parts, an example of which is described in the following specification, pointed out in the appended claims, and illustrated in the accompanying drawings, wherein:

Figure 1 shows a removable bridge employing my particular form of expansive split pin dental appliance.

Fig. 2 shows a top view of a rectangular shaped expansive dental appliance.

Fig. 3 is a view taken upon the line 3—3 of Fig. 2.

Fig. 4 shows the expansive dental appliance removed from the setting of Fig. 3, thus shown apart from its mounting.

Fig. 5 illustrates a certain form of rectangular tube employed in connection with the expansive appliance.

Fig. 6 shows a top view of an expansive pin appliance oblong in cross section.

Fig. 7 shows the appliance of Fig. 6 in side elevation.

Fig. 8 shows an expansive pin appliance before it is shaped and built into an inlay.

Fig. 9 illustrates a view upon the line 9—9 of Fig. 8.

Fig. 10 illustrates a tube employed in connection with the expansive pin appliance.

Fig. 11 shows a removable bridge tooth or removable denture taken out of its setting in the patient's mouth.

Referring still to the drawings, the numeral 1 and numeral 2 designate sound teeth within the patient's mouth, and between which it is desired to install an artificial tooth or removable denture. The two teeth 1 and 2 will be carefully drilled and opened up until they are ready to receive a metallic or gold inlay 3. A mold of cavity formed in the teeth will be made by the ordinary methods used by skilled dental mechanics, and the gold inlay prepared from the mold. A tube 4 will be embedded in the mold of the inlay, and the assembled inlay and tube placed in position in the prepared cavities of the teeth. Slots will next be cut in the wall of the inlay and tube. These slots are formed to receive the removable denture. The solid wall tube is molded in the inlay so that an adequate soldering job can be carried out around the outer portions of the inlay, filling in the inlay to the desired thickness.

An artificial tooth 5 is next built up and has secured to the sides thereof by any method known to skilled dental mechanics, the web 6 integrally formed with an expansive split pin 7. The dental appliance 6—7 will be made of any suitably hard and springy material, and split down the center thereof to provide the completed appliance. In building up the artificial tooth with the integrally formed split pin appliances, the pin appliance will first be taken up for shaping and finishing and handled by the long body thereof as shown in Fig. 8. After it is secured to the teeth and artificial denture completed the upper body portions of the pin 7 will be cut off the right length for fitting into the tube 4.

The denture 5 with its integral expansive appliance will then be inserted in position shown in Fig. 1 with the split pin passed downwardly into the tube of the inlay with the webs 6 resting in the slots of the tube and inlay. The split pin dental appliances are manufactured by splitting the pin body down the center thereof and leaving it solid

at the bottom. The pin will be made of some suitable material which has springingly expansive characteristics so that the pin when spread open as illustrated in Fig. 7 5 will engage the tube of the inlay very tightly when the removable denture is inserted in the patient's mouth. After considerable use of an artificial tooth of the removable type, the fittings thereof become 10 slightly loosened, permitting play. It is, therefore, the purpose of this invention to provide a split pin dental appliance which can be spread open by inserting a knife blade or other tool into the split of the pin. 15 The artificial tooth will then be reinserted into the patient's mouth where it will remain very tightly engaged with the teeth 1 and 2, due to the expansive nature of the spread pin within the tubes of the inlay. 20 Figs. 2, 3, 4 and 5 show a form of rectangular shaped split pin or bar 10 which may be employed for large and heavy teeth, or employed where the round pin would not be desirable to use. The tube shown in Fig. 5 25 shows the square receptacle tubing used in the inlay for receiving the split dental appliance.

Figs. 6 and 7 show an oblong shaped split pin appliance and may be employed to advantage in certain cases.

Figs. 8, 9 and 10 disclose the particular form and shape of cylindrical pin and tube which are employed to build up the removable denture and inlay. The removable 35 denture shown in Fig. 11 shows the completed artificial tooth ready to be installed in a patient's mouth.

This form of dental appliance will meas-

urably improve the present day removable dentures and provide the patient with a removable artificial tooth which can be reinstalled in his mouth in a tight and immovable relation with other teeth.

Having thus described my invention, what I claim as new, and desire to secure by Letters Patent is:

1. A removable denture construction, comprising in combination; a metallic inlay, a tube embedded in the inlay and provided with a slot formed in the wall of the tube 50 and inlay, a split pin made of spring material, and a web attached to the split pin and adapted to lie within the slot formed in the tube and inlay.

2. A dental appliance of the character described, comprising in combination; a slotted tube, a pin split down the center thereof such that the pin may be spread open to frictionally engage the tube, and a web attached to the pin.

3. A dental appliance comprising; a tube with a slot formed therein, a pair of outstanding spring members integrally joined at one end and capable of being compressed together to form an approximately cylindrical body for insertion into the tube, and a web integrally formed on one of the outstanding members said web adapted to lie in the slot of the tube.

4. A dental appliance comprising; a pin 70 split from one end to approximately the other end, and a web integrally formed with the pin at right angles with the plane of the split.

ISAAC BROWN.
